UNITED STATES PATENT OFFICE.

SAMUEL PINKNEY PARKER, OF FRANKLINTON, NORTH CAROLINA, ASSIGNOR TO VANN-MOORE MILLS COMPANY, OF FRANKLINTON, NORTH CAROLINA, A CORPORATION OF NORTH CAROLINA.

ATTACHMENT FOR DOBBY LOOMS.

Application filed February 3, 1927. Serial No. 165,691.

This invention pertains to dobby looms, and consists in an attachment for, or an addition to, such looms whereby they are rendered capable of performing work or producing results of which they were heretofore incapable. The mechanism constituting such attachment or addition is capable of ready application to dobby looms of usual or common type and construction, but will be here shown and described as I have applied it to the well-known Crompton and Knowles dobby loom, now widely used and well adapted to receive it.

The accompanying drawings illustrate the invention in simple and preferred form, and show only so much of the loom as is necessary to make clear my invention as used therewith. All parts not shown may be of usual form, construction and arrangement, and except as herein indicated, all the usual parts of the loom will be retained.

In these drawings:

Figure 1 is a front elevation of the upright members and connecting arches of the loom frame, showing the dobby head with its casing partially broken away to disclose parts of the mechanism, a heddle frame and the straps and springs for moving the same in opposite directions, the heddles being broken away in the mid-section of the group to show portions of the attachment at the rear of said frame, and also showing the pattern-chain support;

Fig. 2, a transverse vertical section on the line 2—2 of Fig. 1, looking in the direction of the arrows;

Fig. 3, a top plan view of a perforate board or plate analogous to the comber board of a Jacquard loom, such being employed as a part of the present attachment.

To avoid confusion of terms I shall use in the following description the term heddle or heddle frame in referring to the usual "harness" or heddle frames with their heddles and actuating connections, and the term "heald" when referring to independently actuated wires or cords each provided with a mail or eye and corresponding generally to the "coupling" employed in Jacquard looms, and comprising the sleeper, mail, hanger and lingoe of such coupling.

The invention is primarily intended to enable ordinary dobby looms to produce a terry fabric with a stripe or stripes extending in

the direction of the warp threads or "ends," 55 and bearing letters, words, numerals or other characters or designs in color contrasting with that of the main body of the web or fabric. Such letters, characters, words or designs are repeated at regular intervals, 60 and the portions bearing these are separated by pileless sections or plain basket weaves of from one to two inches, more or less, extending from one to the other selvage of the web, which sections are subsequently cut 65 through their median portion to separate the individual towels, scarfs, or other articles, the severed edges being thereafter hemmed or otherwise finished to prevent ravelling, 70 and to give a neat appearance.

Though primarily designed or used at present for the manufacture of towels having a terry ground, the invention is applicable to the production of plain ground fabrics having letters, figures or designs 75 formed by bringing to the surface contrasting warp threads.

Referring first to Figs. 1 and 2, the numerals 1 indicate the upright sides of the main frame of a loom connected at their 80 upper edges by front and rear arches 2, as best seen in Fig. 2. 3 indicates the casing or cover of a dobby head, and the numerals 4 indicate harness levers, of which but two can be seen for the reason that the actuated 85 levers fall in one line while the unactuated levers fall into another line, thus producing two lines of which only the foremost lever of each line can be seen when looking at the front of the loom as in Fig. 1. In the drawings (Fig. 2) I have represented a dobby head employing twenty harness levers, and serving ordinarily to actuate or to lift twenty distinct harnesses or heddle frames, which are lowered by gravity aided by the action 90 of springs to ensure quick and right-line movement. Four harnesses and four harness levers are sufficient for weaving the terry fabric of which the body of the towels, scarfs, or other articles is to be made; hence 95 I set apart the forward group of four harness levers and harnesses for that purpose. As these comprise the usual straps attached to the heddle-carrying frames and extending 100 over pulleys on cross rods running from the front to the rear arch and thence to one or another of the four forward harness levers, 105 and the usual springs extending from the

lower bar of said heddle frame to hooks or fixtures at or near the floor, further description of said parts seem unnecessary.

The remaining sixteen harness levers are employed to actuate healds, wires or cords 5 having eyes 6 through which the warp yarns or ends employed in weaving the stripe or band bearing letters, words, figures or designs, are led and by which their shedding action is effected. These healds 5 are attached to cords 7 analogous to the neck cords of a Jacquard loom, the upper ends of each of the cords 7 being attached to one or the other of two oppositely-extending arms of a T-lever 8 pivotally mounted upon a cross rod 9 carried in supports 10 on the front and rear arches 2 of the main frame of the loom. As sixteen T-levers are provided in the particular showing here made, and as each lever has two oppositely-extending arms, thirty-two neck cords are provided, and these control thirty-two warp yarns or ends. If desired, more than one neck cord may be carried by each of the alined arms of the respective levers 8 or of any of said levers, and the number of warp yarns or ends controlled by said levers may be thus multiplied. From the intermediate arm of each T-lever 8, a connecting wire or rod 11 extends to one or another of the harness-actuating levers 4 of the dobby. A contractile spring 12 extends from the intermediate arm of each T-lever 8 in the opposite direction, and is attached to a cross rod 13 carried at its ends in uprights 14 similarly secured to the front and rear arches 2 of frame 1. In the drawings the intermediate arm of each lever 8 extends upwardly and the description is worded accordingly, but said arm may be extended downwardly without changing their action or effect, if the warp yarns be properly threaded.

The dobby levers normally stand in the position of the right-hand lever 4 of Fig. 1, that is, thrown to the right; but when actuated through the medium of the pattern chain 15, assume the position shown by the left-hand lever 4 in said figure. The springs 12 normally hold the T-levers 8 with their intermediate arms thrown somewhat to the right as shown by the rear lever 8 in Fig. 1, and the levers 4 connected with the levers 8 serve, when actuated, to swing the intermediate arms of the T-levers to the left, or to the position indicated by the foremost lever 8 in Fig. 1. With the levers 4 in their normal position and the levers 8 in their normal position (that of the rear lever 8 in Fig. 1), the eyes 6 of the healds 5 will be in common horizontal plane coincident with the eyes of the heddles of frame 16. Those heddles usually occupying the midlength portion of the frames 16 are of course omitted from said frames, being replaced by the healds 5.

If, now, any of said levers 8 be drawn to the left by a dobby lever 4, the right-hand arm of such lever 8 will be raised and the left-hand arm lowered, thus carrying up above its normal level the eye 6 of the heald 5 attached to its right-hand arm, and lowering the heald 5 attached to its left-hand arm. Each heald 5 is provided below the eye 6 with a weight or lingo 17, sufficient to maintain said heald in true vertical position, and to cause the prompt lowering of the heald when the supporting arm of lever 8 with which it is connected is lowered. At the same time those healds connected with the right-hand arms of the actuated T-levers 80 will be raised a distance equal to the lowering of those connected with the left-hand arms, and the warp yarns or ends passing through the eyes 6 of healds respectively so lowered and raised will be moved apart, producing the shed between the warp yarns thus lowered and raised. Such shedding action will occur simultaneously with that of the other warp yarns which is produced by the raising and lowering of alternate heddle frames, and the shuttle will at each reversal of the shed be shot through the newly formed shed and lay therein the weft thread, in the usual manner of weaving.

In producing terry fabric, three picks are, usually, made between each two movements of the lay or lathe which beats up the several picks of yarn laid by the shuttle, and in so doing forms the loops or pile on the upper and lower faces of the fabric, these loops being formed in the warp yarns bound or held by the several picks of weft thread, and caused to buckle or loop upward and downward respectively as the weft picks are driven up into the fell or apex of the shed. This process continues uninterruptedly throughout such length of the web or fabric as is to have the terry formation. In the case of toweling and similar goods, each individual article may, for smaller sizes, have its length in a direction transverse to the warp yarns or ends, or from selvage to selvage, and its width in the direction of said warp yarns, but for larger towels or articles the length will preferably be in the direction 115 of the warp yarns. The terry weave is continued a distance equal to the width of a small towel or article, or equal to the length of a large towel or article, and is then followed by a section of plain or basket weave, sufficient to afford an adequate hem for the proximate sides or ends of two terry sections when the web is cut transversely along the median line of the basket weave section, to separate successive towels or articles.

The raising and the lowering of the warp yarns of the zone or zone stripe or stripes which is or are to bear the letters, words, figures or design, is under control of the healds 5 operated by the T-levers 8, and the

action of said T-levers is controlled by the studs or pins of pattern-chain 15 which control the levers 4 of the dobby. In other words, only those levers 4 for which an actuating pin or stud is placed in any cross bar of the pattern-chain will be moved at the passage of any given pin bar of said chain beneath the fingers or other members of the dobby which bring about the throw of the 10 dobby levers 4. The respective bars will have more or fewer pins according to the number of T-levers 8 to be actuated or controlled by said bars, and these pins will be variously positioned in the respective bars 15 according to the particular warp yarns to be raised and to be lowered respectively through the action of each chain bar in turn. According to the actuation of the T-levers 8, one or another group of warp yarns will be lifted and a corresponding group will be lowered.

The warp yarns or ends for the stripe or stripes, band or bands comprise one set of threads of the same color as the main body 25 of the towel, usually white or a light color, and another set of a contrasting color or shade. In the case of small towels or articles, or towels which are of a width less than the width of the woven web or fabric, 30 the length of the towel is equal to the width of the web, and the selvages of the web form the ends of such towel or article, while the sides are preferably hemmed, though they may be bound or otherwise finished. In the 35 case of larger towels or articles, the selvages of the web will constitute the side edges of the towel, while the ends formed of the basket weave sections between successive towel lengths, will be hemmed or otherwise finished. In every case the longitudinal 40 stripe or band formed in the woven web shows on its upper face only the light or body color except where the warp threads or ends of darker or contrasting color are brought to the upper face of the towel or 45 other article, to form the letters, figures, design or pattern, while on the corresponding lower face or back of the towel, only the white or lighter warp yarns appear in such 50 figures, designs or patterns, the remaining or body portion of the stripe or stripes, band or bands on the under or rear face being of the dark or contrasting color. In other words, the figures, letters, or pattern appear 55 on the upper or front face of the towel only in the darker or contrasting color, and on the lower or rear face of the towel only in the lighter or ground color. The relatively 60 larger and smaller articles differ only in size, and in the fact that in the larger articles the color bands or stripes run lengthwise of the towel or article, or in the direction of the warp threads or ends, while in the relatively smaller towels or articles, said 65 stripes or bands run transversely of the

towels, though still in the direction of the warp threads. The warp yarns for such stripe or band may be wound to present the light and the contrasting colors in alternation or in alternating pairs, according to the 70 quality or weight of toweling or fabric to be produced. When the yarns are arranged side by side in pairs, both yarns of a pair are led through the eye of a single heddle and handled as a single yarn.

For the purpose of guiding the neck cords 7 to the healds 5, I employ a perforated board 35 such as shown in Fig. 3, and analogous to the usual comber board of the Jacquard loom. It is deemed advantageous also 80 to provide two upper perforate bars 36 to divide the neck cords 7 into two distinct groups, those connected with the left-hand arms of the levers 8 constituting one group and those connected with the right-hand 85 arms of said levers constituting the other group. These guides serve to keep the cords and healds properly separated and free from interference, and to direct the neck cords 7 to points directly over the warp yarns of 90 healds 5 and their weight of lingoes 17, so that said cords, healds and weights may move in true vertical lines and be prevented from interfering or becoming entangled one with another. The several guides are 95 conveniently carried by supports secured to and extending downward from the rear arch member of the loom frame, but may be placed in any convenient position.

The pattern-chain 15 and the roll or cylinder 23 which advances said chain bar by bar during the operation of the loom are in the main of usual construction, but the chains connecting the pins-bars 21 are preferably furnished at suitable intervals with 100 small rods or wires 27 extending parallel with said pin-bars and of a length somewhat in excess of the dobby cylinder 23, the ends of which are notched to receive said rods or wires. The purpose of the rods or 105 wires 27 is to form supports for the chain 15 which, as the descending section of said chain falls from the dobby cylinder 23, engage and ride upon curved supporting arms 110 30 secured to the brackets which support the dobby mechanism, or to any other convenient support. In this way the pattern-chain is caused to fall in a series of loops extending downward to a point somewhat 115 above the floor. The outer extremities of 120 guide arms 30 are sustained by supports 31, 32 held at any desired adjustment by a set-screw 33, thus compensating for variation in height or curvature of said arms 30. The outermost stretch of chain constituting the 125 series of depending loops passes upward to and about a cylinder 40 carried by a shaft or axle 39 journaled in upright supports 38 carried by the guide arms 30, said cylinder 130 40 being essentially the same in construc-

tion and size as the dobby cylinder 23. Better to ensure proper wrapping of the pattern-chain about the cylinders 23 and 40, an intermediate loose roll 37 journaled in 5 arms or brackets 34 carried by the supporting frame of the loom or the dobby support, and placed at a lower level than said cylinders 23 and 40, serves to cause the chain to move downward from cylinder 40 and 10 thence upward to cylinder 23 as seen in Fig. 1. This ensures proper retention of the pin-bars 21 in the seats of cylinders 23 and 40. To effect like rotation of the cylinders 23 and 40, a chain 41 passes about like 15 sprocket-wheels on the respective ends of said cylinders, or on the shafts or axles which carry them. No claim is made herein to the chain construction just described, or to the supporting and guiding devices 20 therefor.

The foregoing description contemplates the production of towels with selvage ends and hemmed sides, requiring short plain or basket woven stretches between successive 25 towel sections, but it is obvious that terry fabrics and plain fabrics having a continuous figured stripe, or a plurality of such stripes running lengthwise of the entire web, may be produced through the use of the 30 mechanism here described, and I contemplate such use thereof. The plurality of stripes may be produced either by carrying a plurality of neck cords from each end of each T-lever, or by using a plurality of sets 35 of levers 8 controlling different sets of neck cords and healds, each lever actuating simultaneously at least one ascending and one descending neck cord.

By my invention I am enabled to adapt 40 the common dobby looms now in wide and general use, to the manufacture of fabrics having one or more longitudinal stripes or bands of any desired width and containing suitable designs, letters, words, names or 45 figures, continuous or repeated. The entire mechanism necessary to be added to the ordinary loom consists of relatively few parts of very simple form. They comprise a group of identical T-levers such as 8; cross rods as 9 and 13; four supports such as 10 and 14; identical springs such as 12; and neck cords, healds, and weights or lingoies, or their equivalent, springs, those of each 50 group being identical one with another. They may be applied to existing looms already in operation, by any good mill hand in a very short time, and connected up to 55 operate in the manner described by any fairly experienced weaver. Similarly, the only 60 changes required to be made in the existing dobby mechanism are to groove circumferentially the end portions of the chain-supporting and feeding cylinder; provide the guides 31 and 34; furnish the chains with 65 the wires or rods 27; and add the roll 37

and cylinder 40 and the sprocket chains and wheels for transmitting motion from cylinder 23 to cylinder 40.

It is obvious that dobbies having a greater or lesser number of harness levers than here 70 shown and described, or two separate dobbies, may be used, and a greater number of warp yarns be thus controlled, enabling wider distinctive bands, or a plurality of bands, to be woven; that weights may be 75 substituted for the springs 12; that cords can be substituted for the wires or rods 11; and that other known equivalents may be used. So also, while I have shown the levers 8 of T form, it is obvious that the essential 80 feature of such lever is that it shall have two oppositely extending arms, one of which serves to elevate a warp yarn while the other serves simultaneously to sink another warp 85 yarn. In other words, if actuating connection be made with either of the reversely extending arms, the third arm may be omitted without in any manner changing the mode or principle of action of said levers. 90

Connection between the wires or rods 11 and the levers 8, and between the neck cords 7 and the oppositely extending arms of said levers, may be conveniently made by the common S-shaped hook or lever. This may 95 also be employed in connecting the healds 5 with the neck cords 7, but any common or well-known connection, as a simple tie, may be employed.

I am aware that it has been proposed to 100 utilize a limited number of harness-actuating dobby levers to control the harnesses required to weave a ground fabric, and the remaining dobby levers to control and actuate independent or individual neck cords and healds for producing warp effects or patterns in such fabric; hence I do not broadly claim such utilization of the dobby mechanism. I have, however, devised an exceedingly 105 simple and inexpensive mechanism, readily applicable to and removable from dobby looms already in use, and which, by the employment of rocking levers having two oppositely-extending arms, is capable of controlling twice as many warp yarns as can be 110 controlled by any prior or suggested construction of this nature known to me. 115

What is claimed is:—

1. In combination with harness-actuating 120 levers of a dobby loom, rocking levers having oppositely-extending arms; connections between said levers and the dobby harness levers whereby said harness levers are caused to actuate the rocking levers; cords attached to the outer ends of the arms of the rocking levers; healds independently suspended by the respective cords and each provided with an eye through which a warp yarn or end is carried; and means for moving the rocking 125 levers to normal position after they have 130

been moved from normal position by the dobby harness levers.

2. In a dobby loom, the combination with harness levers of the dobby mechanism, of ⁵ T-shaped levers pivotally mounted on the frame of the loom, each having its two oppositely-extending arms provided with neck cords; guides through which said neck cords pass to position them in proper relation to ¹⁰ the paths of selected warp yarns; healds attached one to each of said neck cords and each provided with an eye for the passage of a warp yarn through it; and means for restoring the T-levers to their normal position ¹⁵ after they are moved by the dobby harness levers from such normal position.
3. In a dobby loom having the usual pattern chain and dobby mechanism for actuating a number of harnesses, and having a suitable number of harnesses for the production ²⁰ of a ground fabric; a series of rocking levers having two oppositely-extending arms; neck cords carried by each of said levers, at least one by each of said arms; healds, one attached to each neck cord and each provided with an eye for the passage through it of a warp yarn; means for drawing and normally holding the rocking levers to one position; and connections between said rocking levers ²⁵ and harness levers of the dobby, whereby ³⁰

each rocking lever is caused, when actuated, to raise one and sink another warp yarn of a selected group.

4. In combination with a dobby loom having the usual harness-actuating dobby levers, ³⁵ harnesses sufficient in number for the weaving of a terry fabric; rocking levers of T shape pivotally mounted on the frame of the loom; connections extending from the intermediate arm of each such lever to one of the dobby ⁴⁰ harness levers; springs, each fixed at one end and connected at the opposite end to the intermediate arm of one or another of the T-levers; neck cords carried by each rocking lever, at least one by each oppositely extending arm thereof; wires or healds suspended from the neck cords, each provided with an eye for the passage through it of a warp ⁴⁵ yarn; and a pattern chain for the dobby having its pins positioned to actuate the dobby levers and consequently the T-levers in proper order to produce predetermined patterns or designs extending longitudinally of the woven web and formed by raising to the upper surface of the web certain of the warp yarns in a given longitudinal zone of the fabric and sinking other yarns therein. ⁵⁰

In testimony whereof I have signed my name to this specification.

SAMUEL PINKNEY PARKER.
